CLAIM

The ornamental design for a notebook computer as shown and described.

DESCRIPTION

FIG. 1 is a front perspective view of a notebook computer showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is another front perspective view thereof of the notebook computer of FIGS. 1-8 in an alternate configuration of use with the display rotated;

FIG. 10 is another perspective view thereof;

FIG. 11 is an enlarged view of the portion, labeled '11' of FIG. 1;

FIG. 12 is an enlarged view of the portion, labeled '12' of FIG. 6;

FIG. 13 is an enlarged view of the portion, labeled '13' of FIG. 6;

FIG. 14 is an enlarged view of the portion, labeled '14' of FIG. 6;

FIG. 15 is an enlarged view of the portion, labeled '15' of FIG. 8;

FIG. 16 is an enlarged view of the portion, labeled '16' of FIG. 8;

(Continued)

FIG. 17 is an enlarged view of the portion, labeled '17' of FIG. 8; and, FIG. 18 is an enlarged view of the portion, labeled '18' of FIG. 8.

The even-dash broken lines illustrate portions of the notebook computer that form no part of the claimed design. The dash-dot broken lines represent the extents of the enlarged views and form no part thereof.

1 Claim, 18 Drawing Sheets
